UNITED STATES PATENT OFFICE.

RICHARD H. WARD, OF YOUNGSTOWN, OHIO.

FEEDING DEVICE FOR ROLLING-MILLS.

No. 839,441.

Specification of Letters Patent.

Patented Dec. 25, 1906.

Application filed January 4, 1906. Serial No. 294,546.

To all whom it may concern:

Be it known that I, RICHARD H. WARD, a citizen of the United States, residing at Youngstown, in the county of Mahoning and State of Ohio, have invented new and useful Improvements in Feeding Devices for Rolling-Mills, of which the following is a specification.

This invention relates to the art of metal-rolling, and more particularly to the feeding means for the material to be rolled or reduced.

To this end the invention contemplates a simple and practical construction of feeding device for rolling-mills.

My invention primarily has in view a construction of feeding device for rolling-mills possessing special utility as a feeder or guide for tin-plate and other kinds of light thin sheet metal to obviate the usual difficulties experienced in feeding light-weight metal to reducing-rolls. Ordinarily in the feeding of this class of material great difficulty has been experienced in the tendency of such material to curl, kink, or buckle, and the present invention provides a construction which secures a proper feed of the plates into the bite of the mill-rolls, while at the same time preventing the plate from kinking, buckling, or curling.

With these and other objects in view, which will readily appear to those familiar with the art, the invention consists in the novel construction, combination, and arrangement of parts hereinafter more fully described, illustrated, and claimed.

The essential features of the invention involved in the mounting of the several rollers of the feeding device are susceptible to some structural modification without departing from the scope of the invention; but a preferred embodiment thereof is shown in the accompanying drawings, in which—

Figure 1 is a vertical transverse sectional view of a rolling-mill, illustrating an applied position of the improved feeding device at the feeding-in side of the mill-rolls. Fig. 2 is a front elevation of the rolling-mill with the improved feeding device applied thereto. Fig. 3 is a top plan view of the feeding device, showing the rolling-mill in section on the line 3-3 of Fig. 1. Fig. 4 is a side elevation of the feeding device, the view also showing its relation to the mill-rolls. Fig. 5 is a top plan

view of one side portion or frame-bar of the feeding device or attachment.

Like references designate corresponding parts in the several figures of the drawings.

The feeding device contemplated by the present invention is designed to be associated with any of the ordinary types of rolling-mills embodying in their general organization the superposed mill-rolls or reducing-rolls 1 and 2, supported in their relation one above the other between the opposite roll-housings 3. The feeding device as an entirety is supported between the opposite roll-housings wholly at the feeding-in side of the rolls 1 and 2 and in a plane to pass the plate directly into the bite of said rolls.

The active elements of the feeding device are a pair of horizontal upper and lower feed-rollers 4 and 5, respectively, and a single friction driving-roller 6, arranged for frictional contact with the surface of one of the mill-rolls and also with the surface of one of the feed-rollers to provide means for transmitting the necessary feeding motion to the rollers 4 and 5, as will be more particularly pointed out. The feed-rollers 4 and 5 are arranged in horizontal positions and in the same vertical plane one above the other. Also the said rollers are located within the angle between the mill-rolls at the feeding-in side thereof, so that the bite of the feeding-rollers is in substantially the horizontal plane of the bite of the mill-rolls and as close to such bite as practicable, so that a comparatively short distance lies between the feeding-rollers and the point where the plate is caught by the mill-rolls, thereby materially contributing to the feeding of the thin plate to the mill-rolls without buckling or curling. In the preferable construction of the feeding device the single friction driving-roller is arranged for contact with the lower mill-roll 2, and hence is located below and in contact with the lower of said feeding-rollers, (designated by the reference-numeral 5.)

In order to properly position and support the several rollers of the feeding device in the locations just referred to, the invention provides improved supporting and adjusting means for the same. Referring thereto it will be observed that the several rollers of the feeding device are associated with what may be termed a "carrying-frame," consist-

ing of oppositely-arranged supporting frame-bars 7, located at opposite sides of the mill and arranged for support upon the opposite roll-housings 3, as plainly shown in Fig. 3 of the drawings.

- 5 The frame-bars are duplicates in construction, and each of the same essentially consists of an approximately straight bar or frame member provided at its outer end with a hand-grip 8 and at its inner end with 10 an upright open bearing-cup 9, receiving one of the journal-spindles 10 of the lower feed-roller 5. Also each of the opposite supporting frame-bars 7 is provided at its inner end portion with an integral pendent inner 15 hanger-arm 11, arranged obliquely and provided at its lower extremity with an attaching-ear 12, designed to receive a fastening-bolt 13, secured in the adjacent roll-housing 15 20 3 to provide a supporting connection for the inner end of the frame-bar. The said inner pendent hanger-arm 11 of each frame-bar 7 is provided therein with a bearing-opening 14, arranged intermediate the bearing-cup 9 25 14, and the lower attaching-ear 12 and designed to accommodate therein a bearing-box 15, provided with an adjustable cap 16, against which operates the set-screw 17, which serves to maintain the proper frictional 30 35 contact of the driving-roll 6 with the mill-roll 2. The bearing-boxes 15 of the opposite frame members or bars 7 receive therein the journal spindles or ends 18 of the said friction driving-roller 6.
- 35 In connection with the inner hanger-arm 11 each of the frame-bars 7 is provided contiguous to its outer end with an outer pendent holding-arm 19, having the longitudinal slot 20 therein to receive the fastening-screw 40 21, secured in the adjacent roll-housing 3. By reason of this construction it will be obvious that before tightening the fastening bolts and screws 13 and 21 for the opposite frame-bars the said frame-bars may be 45 moved by the hand-grips 8 in a vertical direction either up or down to provide for accurately positioning the said rollers of the feeding device in their operative relations to the mill-rolls. Then upon the tightening of the 50 bolts and screws 13 and 21 the entire attachment is rigidly held in position.
- Each of the opposite frame-bars 7 is provided contiguous to its inner end with an up-standing bearing-lug 22, on which is pivotally mounted, as at 23, a holding-lever 24. 55 The holding-lever is pivotally supported intermediate its ends, and at the inner end thereof is provided with an inverted open bearing-cup 25 for a journal-spindle 26 of the 60 upper feed-roller 4. The inner end portion of each holding-lever 24 has a threaded opening 27, receiving a regulating-screw 28, bearing

ing on the frame-bar and serving to adjust the feed-roller 4 to the thickness of the metal being rolled. A pressure-spring 29, 65 interposed between the holding-lever 24 and the frame-bar 7, serves to yieldingly hold the upper feed-roller in contact with the lower feed-roller.

From the foregoing it is thought that the 70 construction, operation, and many advantages of the herein-described feeding device will be readily apparent without further description.

What I claim is—

1. A feeding device for rolling-mills comprising oppositely-arranged supporting frame-bars, a lower feed-roller mounted on the frame-bars, adjustable holders supported on the frame-bars, an upper feed-roller held by said 80 holders and arranged in superposed relation to the lower feed-roller, and driving means for said feed-rollers.

2. A feeding device for rolling-mills, comprising a pair of upper and lower feed-rollers, 85 a friction driving-roller arranged for contact with one of the feed-rollers, oppositely-arranged supporting frame-bars carrying the lower feed-roller and the driving-roller, and adjustable holders supported on the frame- 90 bars and holding the upper feed-roller.

3. A feeding device for rolling-mills comprising a pair of suitably-driven feed-rollers arranged in superposed relation, and a supporting-frame for said rollers consisting of 95 oppositely-located frame-bars having a pivotal hanger-support at their inner ends and an adjustable hanger-support at or contiguous to their outer ends.

4. A feeding device for rolling-mills comprising a pair of superposed feed-rollers, a friction driving-roller arranged for contact with one of the feed-rollers, oppositely-located supporting frame-bars provided at their inner ends with bearing-cups for the 100 journals of the lower feed-roller, and with pendent hanger-arms having attaching-ears and adjustable bearing-boxes for the journals of the friction driving-roller, said frame-bars also having outer shiftable holding- 110 arms, carrier-levers pivotally supported intermediate their ends upon and above the frame-bars and provided at their inner ends with bearings for the journals of the upper feed-roller, and regulating devices mounted 115 in the outer ends of the carrier-levers and engaging the frame-bars.

In testimony whereof I affix my signature in presence of two subscribing witnesses.

RICHARD H. WARD.
